UNITED STATES PATENT OFFICE.

ROBERTO CLEMENS GALLETTI, OF ROME, ITALY.

METHOD OF AND APPARATUS FOR PRODUCING ELECTRIC OSCILLATIONS.

1,028,204.

Specification of Letters Patent.

Patented June 4, 1912.

Application filed January 27, 1908. Serial No. 412,902.

To all whom it may concern:

Be it known that I, ROBERTO C. GALLETTI, a subject of the King of Italy, residing at Rome, in Italy, have invented certain new and useful Improvements in Methods and Apparatus for Producing Electric Oscillations, of which the following is a full, clear, and exact description.

This invention relates to improvements in methods and apparatus for producing electric oscillations, the means employed also enabling the oscillations to be produced continuously at very high potential.

A feature of this invention is that a main oscillating circuit has connected to it a number of auxiliary oscillating circuits so arranged that when discharge takes place in one of the auxiliary oscillating circuits, this discharging circuit automatically sets up a discharge in another of the auxiliary circuits as its own discharge dies out and so on throughout the series, the last auxiliary circuit so discharging acting on the circuit first discharged to again set the series of auxiliary circuits discharging in cyclic order. In consequence of this successive discharge of the auxiliary circuits the main circuit above referred to as connected to each auxiliary circuit is thrown into continuous oscillation, as explained below.

Another feature of this invention is that the capacities in said auxiliary series of oscillating circuits can be arranged so that they are not "directly" connected to the main oscillating circuit referred to above and need not take part continuously in the oscillation of said circuit.

In the accompanying drawings, Figure 1 represents diagrammatically an arrangement of oscillating circuits adapted for use in carrying this invention into effect according to one modification. Fig. 1^a is a diagrammatic view similar to Fig. 1, illustrating another way of carrying my invention into effect. Fig. 2 shows diagrammatically one method of carrying the invention into effect when the capacities in the auxiliary series of oscillating circuits are not "directly" connected to the main oscillating circuit, only two of the auxiliary oscillating circuits being shown, the others being exactly similar.

Referring to Fig. 1, one pole of a dynamo D is connected through a large inductance I,

consisting preferably of copper wire wound on an iron core, to a main oscillating circuit C intended to oscillate continuously. The oscillating circuit C is preferably closed without the formation of a spark or an arc. Besides the oscillating circuit C the figure also shows a series of auxiliary oscillating circuits running from subscript "1" to "n," in which "n" is equal to 4. One terminal of the condenser C' of circuit C is connected as shown to a number of spheres S₁, S₂ . . . S_n. Another series of Spheres S¹₁, S¹₂ . . . S¹_n complementary to these latter is connected to the other pole of the dynamo D through large inductances I₁, I₂ . . . I_n, these inductances being employed to prevent direct communication between the two series of spheres and to protect the dynamo from oscillations. Connecting each pair of spheres S¹₁ S₁, S₂ S₂ . . . S_n S_n respectively are oscillating circuits B₁, B₂ . . . B_n, each of these circuits consisting of a condenser and an inductance connected in series; for instance, auxiliary circuit B₁ comprises a spark gap S₁, S¹₁ and condenser F₁, and inductance G₁, connected in series across the spark gap. Each of these auxiliary circuits B₁, B₂ . . . B_n has one terminal connected to one terminal of the main oscillating circuit C and its other terminal connected to one of the dynamo leads through the inductances I₁, I₂, etc.

With each of the auxiliary circuits above identified there is combined a solenoid marked H₁, H₂ . . . H_n syntonized to the frequency of the auxiliary circuit to which one of its terminals is connected, the other terminal of each of these solenoids, marked S²₁, S²₂ . . . S²_n, being free and placed near the spheres of that one of the auxiliary circuits which it is desired to cause to discharge in sequence immediately following the auxiliary circuit to which the other terminal of the solenoid is connected.

The initial discharge between any one of the pairs of spheres, constituting spark gaps of the several auxiliary circuits, may be brought about by the use of a high tension discharge from a terminal of an induction coil indicated at X in Fig. 1. This coil terminal may be placed adjacent to any one of the pairs of auxiliary circuit spark gaps.

The solenoids H₁, H₂ . . . H_n connected as above described will each attain a very high

potential at their free extremities S''_1 , $S''_2 \dots S''_n$ whenever an electric discharge takes place between the pairs of spheres $S_1 S^1_1$, $S_2 S^1_2$, etc. in the order of coupling 5 of these circuits and their respective solenoids. The auxiliary circuits B_1 , B_2 , etc., will charge and discharge in an endless cycle without further necessity for the application of the discharge from the induction coil X which is used only to break down 10 the di-electric between a single pair of the spheres $S_1 S^1_1$, $S_2 S^1_2$, etc., in the first instance. It is understood that the constants of the several auxiliary circuits will be so 15 chosen as to permit of a sufficient charge to accumulate in each of their condensers from the dynamo source during the cyclic period to enable each of these auxiliary circuits in its turn to sustain the main circuit C in continuous oscillation.

The several auxiliary circuits, as above described, can be so arranged that the free electrode terminals of their solenoids, in conjunction with the several spark gaps, 25 will constitute a complete series, adapted to discharge in succession, or may dispose them in a straight line, as shown in Figs. 1 and 1^a, and bring about the same result by a connector S_x which, of course, would be dispensed with in a series located as first explained.

While I have specifically referred to sphere or ball spark gaps I do not wish to be restricted to that particular agency for 35 effecting a disruptive discharge. Many such devices are known in the art and my invention may be used irrespective of specific limitations in this respect.

It is obvious that instead of connecting 40 the auxiliary oscillating circuits directly to the main oscillating circuits, they may be connected inductively, as shown in Fig. 1^a. The inductive connection is represented in said figure by the inductance L_1 common to 45 all the auxiliary circuits B_1 , $B_2 \dots B_n$, and the inductance L_2 appertaining to the main induced circuit C .

Referring to Fig. 2, one pole N of the dynamo is connected through an inductance 50 I_1 to the main oscillating circuit C ; the oscillating circuit C is also connected as shown to a sphere S_r . A sphere S^1_r , opposite the sphere S_r , is connected through an inductance I_r to the other pole M of the 55 dynamo or other source of potential. The condenser F_r of the oscillating circuit B_r is not, however, as previously described, connected directly to the oscillating circuit C but is connected through a high resistance R_r , the condenser also being connected to a sphere S'''_r which is in such a position 60 as to be within the path of the spark discharge $S_r S^1_r$. A solenoid H_r is connected to a sphere S''_r in proximity to the next

oscillating circuit, not shown. As described 65 with reference to Fig. 1, the oscillating circuit C is connected to a number of oscillating circuits corresponding to that just described in detail. Also, the terminal of the condenser of the circuit B is connected 70 to the oscillating circuit C or else an intermediate terminal may be connected to earth. The terminals M and N may be those of a continuous current dynamo, the various circuits being separated by inductances consisting 75 of copper wire wound on iron cores.

What I claim is:

1. The combination of a closed oscillatory main circuit and a plurality of auxiliary oscillatory circuits connected thereto, and means for charging and discharging the auxiliary circuits in orderly sequence from a direct current source.

2. The combination of an oscillatory main circuit and a plurality of auxiliary oscillatory circuits connected thereto, and means for charging and discharging the auxiliary circuits in orderly sequence from a direct current source.

3. The combination of a main oscillatory circuit and a plurality of auxiliary circuits adjacent to each other, means for charging the auxiliary circuits, means for discharging one of them, and means whereby the latter establishes a discharge in an adjacent auxiliary circuit.

4. The combination of a main oscillatory circuit and a plurality of auxiliary circuits, means for charging the auxiliary circuits, means for discharging one of them, and means whereby the latter establishes a discharge in one of the other circuits.

5. The combination of a main oscillatory circuit, a number of auxiliary oscillatory circuits, a source of direct current, and impedance devices between the auxiliary circuits and the direct current source, substantially as described.

6. The combination of an oscillatory circuit and a plurality of independent oscillatory circuits connected thereto, a common source of direct current, and impedance devices between such source and the independent oscillatory circuits.

7. The combination of an oscillatory circuit and a plurality of independent oscillatory circuits connected thereto, a common source of direct current, impedance devices between such source and the independent oscillatory circuits, and means for discharging these circuits in determinative order.

8. The combination of an oscillatory circuit and a number of separate oscillatory circuits, a source of energization, reactance devices between such source and the separate oscillatory circuits, and secondary oscillatory circuits connected to each of the latter.

9. The combination of an oscillatory circuit and a number of separate oscillatory circuits, a source of energization, reactance devices between such source and the separate oscillatory circuits, and secondary oscillatory circuits interconnecting these separate circuits.

In testimony whereof I have signed my name to this specification in the presence of two subscribing witnesses.
